PROTECTING TRAY FOR VALVE CHAMBERS

Application filed April 1, 1929. Serial No. 351,804.

My invention relates to internal combustion engines of the poppet valve type, and more particularly to engines of the type in which the valve chamber provides an oil reservoir to which oil lines, that lead to the different bearings, are connected.

With the valves and valve guides removed from the engine, incident to grinding the valves and their seats, large openings, extending from the top of the chamber to the top of the cylinder block, are left, through which waste matter is free to fall into the valve chamber. When carbon is scraped from the tops of the cylinders and valve ports, and the valve seats are refaced, the resultant carbon and cuttings fall through the aforesaid openings into the valve chamber, thereby contaminating the oil therein, which frequently results in clogging of the oil lines, ending disastrously in burning out of the bearings.

It is a purpose of my invention to provide a device in the form of a tray which is capable of being readily applied to the valve chamber, and in such position as to form a protecting covering for the oil in the chamber to receive and collect the carbon particles, cuttings, and other waste matter, in such manner as to prevent contamination of the oil.

I will describe only one form of protecting tray embodying my invention and will then point out the novel features thereof in claims.

In the accompanying drawings:

Fig. 1 is a view showing in front elevation one form of protecting tray embodying my invention in applied position to the valve chambers to an internal combustion engine.

Fig. 2 is a vertical sectional view taken on the line 2—2 of Fig. 1.

Fig. 3 is a detailed perspective view of the protecting tray shown in the preceding views.

In carrying out my invention, I provide a device which essentially consists of a tray adapted to be partly inserted into the valve chamber of an engine to seal the oil contained therein against contamination by the

carbon and cuttings, and other waste matter which may fall into the chambers through the valve ports and other openings. The tray, in the present instance, comprises a partition 15 substantially of rectangular outline and corresponding in width to that of the valve chambers to which it is adapted to be applied, but as to length in respect to the valve chambers, it is shorter in order to accommodate flexible end elements 16 that function to span the space between the ends of the partition and the end walls of the valve chambers in such a manner as to seal the ends of the partition against the passage downwardly of carbon and cuttings.

Rising from the back edge of the partition 15 is a substantially vertical flange 17 corresponding in length to that of the partition, and having its upper marginal edge flared rearwardly as indicated at 18 in order that it may have physical contact with the rear wall of the valve chambers and thus prevent the passage of carbon and cuttings downwardly between the flange and wall. Medially of its ends the flange 17 is recessed as indicated at 19 in order to accommodate the bulged part of the motor block. Extending downwardly from the front edge of the partition 15 is a second flange 20, likewise corresponding in length to the partition 15, and designed to span the joint between the partition and the lower edge of the front wall of the valve chambers so as to prevent entrance therethrough of carbon or cuttings, and particularly in the event the partition should be accidentally lifted, it being noted that the flange 20 is relatively wide so as to depend an appreciable distance below the aforesaid edge of the front wall of the chambers.

The partition 15, and the two flanges 17 and 19 are preferably constructed from a single sheet of metal or other suitable material by bending the sheet longitudinally along the lines defined by the front and rear edges of the partition 15. The material of which these elements is formed is sufficiently rigid in nature to maintain the angular relation of the flanges and partition, once they are formed so that the tray will main-

tain its original form and thus at all times be quickly and properly fitted within the valve chambers to effectively perform the functions for which it is intended.

5 The elements 16 are formed of any suitable flexible material such as rubberized fabric, and by means of split rivets 21 these elements are secured to ends of the partition and the ends of the flange 17 in such manner that the elements extend outwardly and upwardly beyond the ends of the tray, and by reason of the nature of the material of which they are formed, they normally maintain this contour except when inserted into 10 a valve chamber, when, by engagement of the end walls of the valve chambers they are flexed inwardly toward each other in a manner to provide an effective seal between the walls of the chambers and the ends of the tray to prevent the passage downwardly of 15 carbon, cuttings and any other waste matter, to a point beneath the partition. It will be understood that with the elements in this position they are held under tension, their tendency being to return to normal position, and in so doing, engaging the end walls of 20 the valve chambers to provide the aforesaid seal. In practice, the tray is applied to the valve chambers of an engine in the manner 25 illustrated in Figs. 1 and 2, the partition 15 assuming a horizontal position within the chambers and above the body of oil contained therein so as to provide a protecting covering for the oil. The flanges 17 and 20 30 are positioned and so engage the walls of the chambers as to support the partition in proper covering relation to the oil, and in addition, coact with the walls of the chambers to prevent carbon particles and metal 35 cuttings from passing downwardly at the front and rear edges of the partition, the elements 16 performing a similar function at the ends of the partition, as has been described. With the tray applied in the manner 40 described, it will be manifest that it protects the bottom of the valve chamber against any waste matter falling into the oil either through the top openings of the chambers or the side openings thereof, and 45 in consequence of which, the oil is protected against contamination and its usefulness preserved.

50 Although I have herein shown and described only one form of protecting tray for valve chambers embodying my invention, it is to be understood that various changes and modifications may be made herein without departing from the spirit of the invention and the spirit and scope of the appended 55 claims.

60 I claim:

65 1. A tray of the character described, comprising a partition, and means secured to and so positioned on the partition as to engage parts of a valve chamber when applied

thereto in a manner to retain the partition substantially horizontal within the valve chambers so as to cover the oil contained in the chamber.

2. A device of the character described, 70 comprising a tray having flexible portions at its ends so positioned as to be placed under tension when the tray is applied to a valve chamber to seal the ends of the tray against the passage of waste matter downwardly 75 between the ends of the tray and the walls of the valve chambers.

3. A device of the character described, comprising a tray having a horizontal partition, a flange rising from the back of the 80 partition and a second flange depending from the front of the partition.

4. A device of the character described, comprising a tray having a horizontal partition, a flange rising from the back of the 85 partition and flexible elements at the ends of the partition.

5. A tray of the character described, comprising an elongated partition, flanges secured to and extending in opposite directions from the partition, and flexible elements secured to the ends of the partition and the ends of one of the flanges. 90

6. A tray of the character described, comprising a partition adapted to be disposed to substantially horizontal within a valve, and means secured to its edges and so positioned thereon as to engage the walls of the valve chambers to seal the partition against the passage of waste matter downwardly there 95 around. 100

7. A tray of the character described, comprising a partition, upstanding and depending members on the partition, and flexible elements at the ends of the partition. 105

8. A tray as embodied in claim 7 wherein the flexible elements are secured to the underside of the partition and to the rear side of the upstanding member in such manner as to cause the flexible elements to extend outwardly and upwardly. 110
